US0D1067632S

(12) **United States Design Patent** (10) **Patent No.:** **US D1,067,632 S**
Zhong (45) **Date of Patent:** **** Mar. 25, 2025**

(54) **VACUUM COMPRESSION BAG**

(71) Applicant: **Shenzhen Zelin Innovation Technology Co., Ltd.**, Shenzhen (CN)
(72) Inventor: **Jiadong Zhong**, Shenzhen (CN)
(73) Assignee: **Shenzhen Zelin Innovation Technology Co., Ltd.**, Shenzhen (CN)
(**) Term: **15 Years**
(21) Appl. No.: **29/965,668**
(22) Filed: **Sep. 27, 2024**
(51) LOC (15) Cl. **03-01**
(52) U.S. Cl. **D3/301; D3/274; D9/709**

(58) **Field of Classification Search**

USPC D3/201, 215, 216, 217, 221, 224, 226, D3/230, 231, 232, 233, 245, 246, 254, D3/273, 274, 276, 278, 280, 283, 284, D3/285, 286, 287, 288, 289, 290, 291, D3/299, 300, 301, 302, 303, 900, 901, D3/902, 903; D9/703, 705, 708, 709
CPC A45C 1/00; A45C 1/02; A45C 3/00; A45C 3/001; A45C 2003/002; A45C 3/004; A45C 2003/007; A45C 2003/008; A45C 3/02; A45C 3/04; A45C 3/045; A45C 3/06; A45C 3/10; A45C 3/12; A45C 7/00; A45C 2007/0004; A45C 2007/0013; A45C 7/0059; A45C 7/0063; A45C 7/0068; A45C 7/0077; A45C 7/0081; A45C 7/0086; A45C 7/009; A45C 11/001; A45C 11/002; A45C 11/003; A45C 2013/028; A45C 13/03; B65D 81/00; B65D 81/2007; B65D 81/2015; B65D 81/2023; B65D 81/2038

(57) **CLAIM**

The ornamental design for a vacuum compression bag, as shown and described.

DESCRIPTION

FIG. 1 is a front perspective view of a vacuum compression bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

1 Claim, 8 Drawing Sheets
